DESIGN FOR A DRINKING GLASS

Albert M. Spinelli and Benjamin Greenstein,
Philadelphia, Pa.

Application April 16, 1936, Serial No. 62,172

Term of patent 3½ years

To all whom it may concern:

Be it known that we, Albert M. Spinelli and Benjamin Greenstein, citizens of the United States and residents of Philadelphia, in the county of Philadelphia and State of Pennsylvania, have invented a new, original, and ornamental Design for a Drinking Glass, of which the following is a specification, reference being had to the accompanying drawing, forming part thereof.

We claim:

The ornamental design for a drinking glass as shown.

BENJAMIN GREENSTEIN.
ALBERT M. SPINELLI.
